(No Model.)

T. J. BERENS.

CHILD'S CRADLE.

No. 391,292.

Patented Oct. 16, 1888.

UNITED STATES PATENT OFFICE

THEODORE J. BERENS, OF CINCINNATI, OHIO.

CHILD'S CRADLE.

SPECIFICATION forming part of Letters Patent No. 391,292, dated October 16, 1888.

Application filed June 14, 1888. Serial No. 277,055. (No model.)

To all whom it may concern:

Be it known that I, THEODORE J. BERENS, a citizen of the United States, residing at Cincinnati, in the county of Hamilton and State 5 of Ohio, have invented new and useful Improvements in Children's Cradles, of which the following is a specification.

This invention relates to improvements in the cradle for which Letters Patent No. 169,123 were granted to Jacob Sprengard October 26, 1875; and my invention has for its object to provide novel, economical, and simple means for operating the locking-catches which connect and disconnect the rocking 15 frame with the platform-base, whereby I dispense with the cylinder for the catch-operating cords, which cylinder is objectionable in that it cuts the latch operating cords.

In the accompanying drawing the figure is 20 a vertical cross-sectional view of a rocking cradle or crib, illustrating my improvement.

Referring to the drawing, the numeral 1 designates a foot or end piece, two of which connected by a brace, 2, form the stationary 25 base or supporting-frame of the cradle. To each end piece is secured a guide-block, 3, having in its center a slot or opening, 4, which extends nearly to the bottom of said guide-block and is preferably wider above than below. The cradle-rockers 5 are supported on 30 the end pieces, 1, between the guides 3, and a pin, 6, on each rocker projects horizontally into the adjacent slot 4, so as to prevent side slipping of the cradle-body when it is being 35 rocked. It will be observed that the loose engagement of the pin 6 and slot 4 will not interfere with the oscillation of the cradle, although it furnishes a simple and effective means of preventing side slipping of the rockers on 40 their supports. The slots 4 and pins 6 also prevent the cradle from being overturned. To the inside of one or both rockers, near each end, are attached pivoted catches 7, each of which is formed with a notch, 8, to engage an 45 adjacent pin, 9, on the cradle-base. When these catches and pins are engaged, the cradle will be incapable of rocking and will be converted into a stationary bed or crib.

In order to raise the catches 7 and hold them 50 disengaged from the pins 9, I provide the following novel arrangement of rigid wires. On the end of the end board of the crib is arranged to move lengthwise a vertical rigid

wire, 10, having its upper end formed into a ring or eye, 11, to engage a projecting pin, 12, 55 fixed to the end board of the crib. To the lower end of the lengthwise-movable wire 10 are jointed divergent rigid wires that connect with the catches, so that by simply drawing the lengthwise-movable wire 10 upward and 60 hanging its ring or eye 11 on the pin 12 the catches 7 are held out of engagement with the pins 9. By disengaging the ring or eye 11 from the pin 12 and forcing the lengthwise-movable wire 10 downward the catches 7 are 65 positively moved into engagement with the pins 9 by reason of the rigid character of the wires. This is a more desirable arrangement than flexible cords.

By raising the chain 10 and connecting the 7c ring 11 to the projecting pin 12 the catches 7 will be lifted and held so as to permit the cradle to be rocked, while by disengaging the ring 11 and projecting pin 12 the catches 7 will drop into engagement with the pins 9 75 and change the cradle into a stationary bed.

I do not wish to be understood as claiming the features of construction shown in Letters Patent Nos. 169,123 and 200,805, as such do not constitute my improvement. I not 8c only dispense with the pivots for the rocking levers and links in the one case, but with the guiding-cylinder in the other case, which cylinder is objectionable in that it cuts the cords. I also dispense with the pivoted cord-holding 85 lever by providing the vertical lengthwise movable rigid wire with a ring or eye to hang on a pin secured to the end of the crib or cradle.

What I claim is— 90
The combination, with the platform-base, the rocking crib or cradle having its end board provided with the projecting pin 12, and the pivoted catches 7, of the lengthwise movable rigid wire 10, rising or falling on 95 the crib or cradle and having at its upper end the ring 11 to engage the projecting pin and at its lower end provided with the hinged divergent rigid wires secured to the catches, substantially as shown and described. 100

In testimony whereof I affix my signature in presence of two witnesses.

THEO. J. BERENS.
